(57) **CLAIM**

The ornamental design for a light fixture, as shown and described.

DESCRIPTION

This application is related to commonly assigned Application No. 10/757,623 filed January 14, 2004, now pending, and to commonly assigned, concurrently filed Application No. 29/221,185, Application No. 29/221,186, Application No. 29/221,153, Application No. 29/221,154, and Application No. 29/221,155, the full disclosure of which are incorporated herein by reference.

FIG. 1 is an isometric view of a first embodiment of the light fixture of the present invention;

FIG. 2 is a front elevation view thereof, the side and rear elevation views being identical thereto;

FIG. 3 is an enlarged top plan view thereof; and,

FIG. 4 is a bottom plan view thereof.

The broken line showing is for illustrative purposes only and forms no part of the claimed invention.
